Primary Examiner — Patricia Palasik(74) *Attorney, Agent, or Firm* — Leydig, Voit & Mayer, Ltd.(57) **CLAIM**

The ornamental design for a shield for puncturing device, as shown and described.

DESCRIPTION

FIG. 1 is a perspective view of a shield for puncturing device according to the present invention;

FIG. 2 is a side view;

FIG. 3 is a side view, opposite of the side view in FIG. 2;

FIG. 4 is a side view;

FIG. 5 is a side view, opposite of the side view in FIG. 4;

FIG. 6 is a top view; and,

FIG. 7 is a bottom view.
